Primary Examiner—Celia Murphy(74) **Attorney, Agent, or Firm**—Sand & Sebolt**CLAIM**

The ornamental design for disc retaining device, as shown and described.

DESCRIPTION

FIG. 1 is a perspective view showing a disc retaining device showing our new design;

FIG. 2 is a top plan view of FIG. 1;

FIG. 3 is a right side elevation view of FIG. 1; and,

FIG. 4 is a front elevation view of FIG. 1.

The broken lines are for illustrative purposes only and form no part of the claimed design.
